UNITED STATES PATENT OFFICE.

JOHN H. NEUMAN, OF PROVIDENCE TOWNSHIP, BUENA VISTA, IOWA.

DISK SHARPENER.

Application filed January 24, 1922. Serial No. 531,445.

To all whom it may concern:

Be it known, that I, JOHN H. NEUMAN, a citizen of the United States, residing at Providence Township, in the county of Buena Vista and State of Iowa, have invented certain new and useful Improvements in Disk Sharpeners, of which the following is a specification.

This invention relates to new and useful 10 improvements in disk sharpeners.

The primary object of this invention is to provide a machine or device of this character which is simple and economical in construction, highly efficient in operation 15 and whereby the operation of sharpening the disks may be greatly expedited.

With the foregoing and other objects in view that will readily appear as the nature of the invention is better understood, the 20 same consists in the novel features of construction, combination and arrangement of parts illustrated in the drawings and more particularly pointed out in the appended claim.

25 In the accompanying drawings, which are for illustrative purposes only and are therefore not drawn to scale:—

Figure 1 is a front elevational view, illustrating the application of my invention.

30 Figure 2 is an end view.

Figure 3 is a vertical transverse section, taken on line 3—3 of Figure 1.

Figure 4 is a similar view, taken on line 4—4 of Figure 3, with the parts represented 35 on an enlarged scale.

Figure 5 is a plan view.

Figure 6 is a front elevation of my device, with the disks removed.

Figure 7 is an end view and Figure 8 a 40 vertical transverse sectional view of an adjustable bearing for one end of the disk shaft.

Referring to the drawings for a more 45 particular description of my invention, and in which drawings like parts are designated by like reference characters throughout the several views, my machine or device comprises a supporting frame A, consisting of the base 1 of wood or other suitable material 50 and the upright metal standards 2 and 3, respectively, connected together by a pair of horizontal laterally spaced longitudinally disposed brace rods 4. These brace rods are

provided at one end with depending hooks 5 which engage apertured brackets 6 carried 55 by standard 2 and are arranged with their opposite ends 7 extending through the standard 3 and equipped with collars 8 which are held against the outer face of the former by set screws 9 or other equivalent 60 means.

In practice, shaft 10 carrying the gang or series of disks to be sharpened, is mounted in position with one end operatively engaging the stub shaft 11 of gear 12 and its opposite end engaging the adjustable bearing 13 carried by standard 3. Gear 12 is driven by a belt 14 working over a pulley 15 carried by the adjacent end of shaft 16 and driven from a motor (not shown) or other 70 source of power, the gear 12 and shaft 16 being connected together by a train of low speed gears 17. Shaft 16 extends longitudinally through and is journaled in the standards 2 and 3. This shaft is square in 75 cross section and provided with a worm 18 longitudinally movable thereon, which intermeshes with a pinion 19 journaled on shaft 20 in the housing 21, which is also movable longitudinally on the aforesaid shaft with 80 the worm. The shaft 20 extends through and beyond an extension 22 of the housing and is provided at its front or forward end with an emery wheel 23 adapted to successively engage the edges of the plow or harrow disks.

In carrying out my invention, I provide a rigid bar 24, consisting of a curved arm 25 secured to the extension 22 of the housing 21 and a straight arm or handle 26 and pivoted at its rear end to the outer end of said curved arm, as at 27, to swing in a horizontal plane, is a hand lever 28 carrying a roller 29 which works against the concave face of the disk to be sharpened, and provides means whereby the grinding wheel 23 may be held against the disk with the desired pressure. The handle and lever 26 and 28, respectively, also provide means for raising the grinding wheel and associated parts in the arc of a circle preparatory to engaging it with the next disk to be sharpened. To facilitate the mounting of the plow or harrow disks in position for grinding, I provide a hoist comprising 100 flexible elements 30 connected with and 105

adapted to wind upon the horizontal shaft 31 and provided at their free ends with hooks 32. Shaft 31 is removably journaled on the standards 2 and 3, provided at one end with a suitable crank or handle 33 and held against reverse rotation by the pawl and ratchet 34 and 35.

The shafts 11 and 16 are so geared that while the emery wheel runs against the edge of the disk to be sharpened, the disk turns slowly so that every point is equally sharpened.

From the foregoing description taken in connection with the drawings, it is thought that the construction, operation and advantages of my invention will be readily understood without requiring a more extended explanation.

Various changes in the form, proportions and minor details of construction may be resorted to without departing from the principles or sacrificing any of the advantages of this invention as defined in the appended claim.

Having described my invention, what I

claim as new and desire to secure by Letters Patent, is:—

Apparatus for sharpening disks mounted upon a disk shaft comprising a frame, means carried by the frame for supporting and turning the disk shaft, a noncircular shaft journaled upon the frame, means for rotating said noncircular shaft simultaneously with the disk shaft, a worm member slidably mounted upon the noncircular shaft, a housing loosely mounted upon the noncircular shaft and receiving the worm member, a shaft journaled in the housing, a worm wheel fixed to the last mentioned shaft and meshing with the worm member, a grinding wheel carried at the end of the last mentioned shaft, a curved handle bar fixed to the housing, a lever fulcrumed to the handle bar and a roller journaled upon the lever and arranged to rotate in a plane lying at a right angle to the plane in which the grinding wheel rotates.

In testimony whereof I affix my signature.

JOHN H. NEUMAN.
